BUNG

Edward A. Rasbridge, Lebanon, Pa.

Application November 6, 1933, Serial No. 696,849

3 Claims. (Cl. 217—113)

My invention relates to bungs for beer kegs and similar containers and has for its principal object to provide a sleeve permanently fitted in the bung opening and having an internal bushing adjacent its outer end to form a liquid tight seal for the tap when inserted in the sleeve and also including a removable plug at the inner end of the sleeve to be knocked out by the siphoning rod of the tap.

10 Beer taps at present are manufactured in various sizes and difficulty has been experienced in furnishing kegs with bungs suitable for accommodating all types of taps and the present improvement has been designed to provide a standard bung having a removable plug capable of use with taps of different sizes and at the same time insuring a liquid tight seal for the tap.

Another object is to provide a bung having an internal shoulder forming a stop for the tap and thus limiting the penetrating movement of the tap in advance of striking the removable plug whereby to prevent removal of the plug until the tap has been properly fitted in the bung.

20 An additional object of the invention is to provide a bung of simple and practical construction, which is inexpensive to manufacture and otherwise well adapted for the purposes for which the same is intended.

25 Other objects and advantages reside in the details of construction and operation more fully hereinafter described and claimed, reference being had to the accompanying drawing forming part hereof wherein like numerals refer to like parts throughout, and in which.

30 Figure 1 is a fragmentary sectional view of a keg showing my improved bung in position and ready to have the plug knocked in by the tap rod;

35 Fig. 2 is a longitudinal sectional view of the bung sleeve; and

40 Fig. 3 is an end view thereof.

Referring now to the drawing in detail, wherein for the purpose of illustration I have disclosed a preferred embodiment of my invention, the numeral 5 designates a beer keg having a bung opening 6 and within which is permanently secured a metallic sleeve 7. The bore of the sleeve is stepped to provide sections having successively reduced diameters as indicated at A, B and C, the outer and larger section A accommodating a packing ring or bushing 8 of cork or similar material to provide a liquid tight seal about the tap 9 when the latter is driven therein.

45 The section A of the sleeve as well as the bushing 8 is slightly tapered to insure a tighter fit for the tap, the shoulder 10, defining the sections A and B serving as a stop for the inner edge of the bushing.

50 The shoulder 11 defining the sections B and C serves as a stop for the tap to prevent penetration thereof beyond the section B and thus sep-

5 arates the tap from a plug 12 which is fitted in the inner end of the sleeve. This plug may then be driven out of the sleeve and into the keg by the rod 13 of conventional construction forming a part of the tap and which is slidably carried thereby. The shoulder 11 is preferably bevelled to act as a guide for the rod 13 during the driving action.

It is believed the manner of use of the device and its advantages will be readily apparent to 10 those skilled in the art from the foregoing. The tapering bushing 8 will accommodate the various sizes of taps in use at present and permit the driving of the tap into the bung to insure a liquid tight fit therein before the plug 12 is removed. 15 The rod 13, which is slidable in the tap is then forced against the plug to drive the latter into the keg whereupon the contents may be withdrawn in the usual manner.

20 While I have disclosed a preferred embodiment of my invention it is obvious that certain changes in construction may be made without departing from the spirit of the invention or the scope of the appended claims.

Having thus described my invention, what I 25 claim is:

1. A bung for kegs comprising a sleeve fitted into the bung opening of the keg and capable of receiving a tap device including a siphoning rod, the bore of said sleeve having a plurality of 30 shoulders defining sections of successively reduced diameters, a packing bushing fitted in said outermost section, a removable plug in the innermost section of the sleeve to be driven into the keg by the siphoning rod, one of said shoulders 35 constituting a stop for the inner end of the tap and said shoulder further being bevelled to guide the siphoning rod into the innermost section to contact the plug.

2. A bung for kegs comprising a sleeve fitted 40 into the bung opening of the keg and capable of receiving a tap device, a plurality of stops spaced longitudinally in the bore of the sleeve, a packing bushing having one edge abutting one of the stops to limit inward movement thereof, 45 the other of said stops being engaged by the tap to limit inward movement thereof and a removable plug in the sleeve to be driven into the keg upon contact by an element of the tap.

3. A bung for kegs comprising a sleeve fitted 50 into the bung opening of the keg capable of receiving a tap device, the latter including a siphoning rod, said sleeve having a bore extending therethrough with one end enlarged, a packing bushing in said enlarged end, a removable plug in 55 the other end of the bore to be driven into the keg upon contact by the siphoning rod and stop means in the bore between the bushing and the plug to limit inward movement of the tap device.

EDWARD A. RASBRIDGE. 60
